BELL TYPE GASSING AND VACUUMIZING APPARATUS FOR DEHYDRATED PRODUCTS

Herbert Robert Heim, Chicago, Ill., assignor to Continental Can Company, Inc., New York, N. Y., a corporation of New York

Application June 15, 1944, Serial No. 540,528

11 Claims. (Cl. 226—82)

1

In the preparation of packages of materials under seal, it has been found advantageous to replace the air by an inert gas, and to employ evacuation during the closing operation. Various structures have heretofore been proposed by which this procedure could be accomplished, including the use of means for presenting a cover to the container after the expulsion of air had been accomplished or to provide a loosely fitted cover on the container, and then displace this during the steps of vacuumizing and gas-filling.

This invention is concerned with an apparatus for the purpose, by which the container with a loose cover thereon is placed in position and thereafter a bell is lowered over the container to provide a chamber within which the container is subjected to the desired operation.

A feature of the invention is the provision of means by which the cover may be displaced from the container and held in a spaced position with respect thereto, these means being made effective by the operation of lowering the bell around the container.

Another feature of the invention is the provision of a cover-lifting structure in association with the bell, which has elements which are normally out of the path of relative movement with respect to the cover, but are moved into an engaging position as an incident of lowering the bell, and are made effective for displacing the cover into the aforesaid spaced position; and are effective during the subsequent removal of the bell for returning to their prior position and disposing the cover in proper place upon the container.

A further feature of the invention is the provision of a cover-lifting structure in which the parts are acted upon by gravity wherewith the weight of the bell is employed in lifting the cover, and the weight of certain cover-lifting parts is employed during the removal of the bell for restoring the parts to initial position along with the placing of the cover in position on the container.

With these and other features as objects in view, an illustrative form of practicing the invention is shown in the accompanying drawings, in which:

Figure 1 is an upright section through the bell and associated parts, with a container in position on the bell platform and with the bell shown in the position attained during lowering and just prior to the sealing of the bell chamber.

Figure 2 is a corresponding section, with parts omitted, showing the cover-lifting parts at an intermediate stage of energization, and ready to begin lifting of the cover.

Figure 3 is a section corresponding to Fig. 2, and showing the bell in sealing position on its platform, and with the cover lifted.

Figure 4 is a horizontal sectional view showing

2

the cover lifting parts substantially on line 4—4 of Fig. 3.

Figure 5 is an exploded view, corresponding to a part of Fig. 4, but with the elements prior to assembly.

Figure 6 is an enlarged upright sectional view substantially on line 6—6 of Fig. 4, corresponding to a part of Fig. 3, with the cover-lifting elements supporting the cover in raised position.

Figures 7, 8 and 9 are perspective views illustrating details of the cover-lifting structure.

Figure 10 is a perspective view, in exploded form, showing the general relationship of parts of a stop member prior to assembly.

Figure 11 is a detailed view of a modified container engaging structure.

In these drawings, a bell platform P has an upper surface for engagement by the bell B for forming a closed chamber, a gasket G being normally interposed for assuring the seal. The bell can be raised and lowered by appropriate means such as a cable C connected to its upper end. Standards S serve as guides along which may slide the blocks K, so that the bell is compelled to rise and fall essentially vertically in the illustrated form.

Gauge pins D are provided on the platform for determining a proper position of a container X, being positioned in accordance with the shape and size of this container whereby to assure that the upper end of the container is presented in an essentially predetermined position within the bell.

External gassing and evacuating means are illustrated in Fig. 1 as comprising a manually operable valve V—1 by which an inert gas such as carbon dioxide, nitrogen, etc., may be introduced from a tank T. Similarly, the manually operable valve V—2 permits evacuation by a suitable means such as a suction conduit M and a filter N. In the illustrated form, the gassing and evacuation conduits are connected to a common conduit H which opens through the platform P, and this platform may be provided with radial channels J for communication with the space between the bell B and the container X.

The upper end of the container has a horizontal wall 13 which is turned upwardly to provide a collar 14 forming the mouth of the container. The container cover Y is shown in Fig. 1 as resting loosely upon the collar 14, and as having the downwardly turned peripheral flange 15 which later will be sealed to an outwardly extending flange at the upper end of the collar 14. The particular shape and arrangement of the container and cover constitutes no part of the present invention, save and except as the structures thereof cooperate with the structures herein claimed.

The upper closing end of the bell B receives the securing bolts 17 which pass through the

spacer blocks 18 and engage in a cover-lifting device. It will be understood that the size of the blocks 18 can be varied appropriately with respect to the height of the bell B and the height of the container X, in order to assure proper operation of the parts.

The cover lifting structure is formed essentially as a ring 20, with elements for lifting the cover and stop elements for determining the position of the cover when lifted. In the illustrated form, the ring is formed of three segments (Fig. 5) which are welded to the interposed blocks 21, these blocks having threaded apertures 22 for the bolts 17. The blocks likewise have kerfs 23 at their inner ends, and are provided (Fig. 7) with aligned apertures 24 for receiving pivot pins 25 (Fig. 6) for supporting the corresponding lifting dogs 26. Each block 21 also has an aperture 27 through which passes a pivot pin 28 (Fig. 6) for supporting the corresponding lifter shoe 30 (Fig. 9). Each lifting dog 26 (Fig. 8) has a rounded actuating surface 26a for engagement during movement of the bell whereby to cause rocking of the dogs inwardly toward the container cover. In the illustrated form, each dog 26 has a lifter shoe 30 with a curved nose 30a for easy sliding over the container wall, and with ears 30b for engaging the pivot 28. The shoes 30 may be dispensed with if the top wall 13 is smooth and has a low frictional constant, and in this case the dogs 26 both engage the container for actuation and also serve as lifters; but their inclusion is preferred, as the compounding effect of the two rocker elements assures engagement and actuation. Owing to the location of the pivots 25 in the illustrated form, the sections of ring 20 are formed with grooves 25a at their bottoms, for insertion and removal of the pivots.

Spaced from these blocks 21 are the stop fingers 31 which are screwed to the ring 20. Each ring section is illustrated as having a notch 32 beneath the position of the finger 31, into which fits the upwardly projecting abutment 33 of a guide block 34 (Fig. 10) which likewise is secured to the ring 20 by a screw 35 (Figs. 1 and 4). The blocks 34 may be chamfered for guiding engagement with the container cover. The blocks 34 and ring 20 have a smooth internal periphery which is slightly greater than the diameter of the covers Y, e. g. about $\frac{1}{2}$ inch on the diameter for a #10 end.

The inner wall of the bell B preferably has the inclined guide blocks 50 for engaging the top flange of the container and assuring the correct relative position of parts when the bell B has been seated on the platform.

When the bell is suspended from its cable C, the lifting dogs 26 hang loosely suspended (Fig. 1) and the center of gravity is so positioned with respect to the pivot pin 25 that the dogs are then free of the path of relative movement of the cover Y as the bell B is lowered. In addition, the lifter shoes 30 likewise have moved loosely by gravity about their pivots 28 until they are also in the position of Fig. 1.

As the bell B is lowered, the lifter shoes 30 engage and are detained by the top wall 13 of the container and are thereby withheld from farther downward movement beyond the top wall, 70 by reason of the pressure of the bell, these lifter shoes are caused to rock about their respective axes 28 during the further downward movement of the bell B, so that the inner ends move inwardly toward the axis of the support ring 75

structure 20, and ultimately engage the lifting dogs 26. It will be noted that the ends of the shoes 30 are curved, so that they can slide easily along the top wall 13 of the container.

Continued downward movement of the bell causes the shoes 30 to rock the lifting dogs 26 inwardly to the position of Fig. 2, in which these dogs have come into contact with cover Y below its edge 15.

The final seating movement of the bell B is accompanied by a further rocking of the lifting shoes 30 and therewith of the dogs 26, and during this rocking of the dogs 26, these dogs individually act as levers which receive downward force components at their pivots 25, and are thereby raised at their inner edges or noses so that the noses or free edges of these dogs cause a lifting of the cover Y to the position shown in Fig. 3. The maximum lifting of the cover Y is determined by the pressing of this cover against the stop fingers 31, as shown in Fig. 3; but it will be understood that containers of a given nominal size will differ somewhat in actual heights; and that by adjustment of the parts for the maximum height for the nominal size, the degree of rocking of the dogs, through the different angles determined by the tolerance of actual heights, will assure a lifting of each and every cover for gassing operations.

At this completion of the downward movement of the bell B, its gasket G is seated upon the platform P. By operation of the valves V-1, V-2, the container can be evacuated for removal of air, and then an inert gas can be introduced for replacing the vacuum. Evacuation and gassing can be repeated if desired.

When the treatment has been concluded, the last operation of gassing has restored the bell chamber to essentially atmospheric pressure, so that it can now be easily lifted by its cable C, and therewith the lifting shoes 30 and lifting dogs 26 tend to rock backwardly by gravity toward and into the positions shown in Fig. 1. During the course of this movement, the lifting dogs 26 lower the cover Y into its prior position upon the container X, so that when the bell B has been lifted above the top of the container, the latter may be removed with the cover in position thereon for preventing the further access of the air. The container X and its cover Y can then be operated upon by a suitable device for interengaging the flange 15 with the flange on the collar 14.

A new container is placed upon the platform P, in the position determined by the gauge pins D, the bell lowered, and the other operations repeated, as before.

When the top wall 13 of the container X has circular corrugations (Fig. 11), it is preferred to provide the lifter shoes 30 with downward projections 30c, which may be solder spots or brazed materials which are rounded to travel over the corrugated surface.

By securing the ring 20 to the bell B at the peripheral portions which support the lifting elements, with inclusion of the spacer blocks 18, a very strong and rigid assembly is provided, and no flexing of the ring 20 occurs. During the lifting of the cover Y, it is guided by the blocks 34, so that the cover Y is held in position for accurate return to closing position upon the container X.

It is obvious that the invention is not limited to the form of construction shown, but that it

may be modified in many ways within the scope of the appended claims.

Having thus described the invention, what is claimed as new and desired to be secured by Letters Patent is:

1. An apparatus of the class described having a platform and a bell for engaging the platform to provide a treating chamber for a container having a cover loose thereon, comprising pivot supports carried inside the bell, lifting means pivoted to the pivot supports and including actuating parts for engaging the container as the bell is lowered and lifting parts moved by the actuating parts for engaging and lifting a container cover from the container, and guide means for detaining the cover in position for being returned to the container mouth when the bell is lifted again.

2. An apparatus of the class described having a platform and a bell for engaging the platform to provide a treating chamber for a container having a cover loose thereon, comprising lifting means inside of and supported by the bell, said lifting means including lifting dogs pivoted for rocking toward and from the cover, and also including lifter shoes pivoted for rocking upon engagement with the container and therewith effective for rocking the dogs into engagement with the cover and for causing the dogs to lift the cover from the container.

3. An apparatus as in claim 2, in which the dogs and shoes are pivoted eccentrically to their respective centers of gravity whereby they fall into initial position by the action of gravity when the bell is lifted and therewith effect return of the cover to the container mouth.

4. An apparatus of the class described having a platform and a bell for engaging the platform to provide a treating chamber for a container having a cover loose thereon, comprising a ring rigidly fixed inside the bell, peripherally spaced lifter dogs pivoted to said ring to rock toward and from the cover between first positions free of the cover and second positions of engagement beneath the cover, and means energized by engagement during the downward movement of the bell for causing said lifter dogs to move from their first positions into said second positions and also causing the said lifter dogs to lift the cover to a position in which the container mouth is open.

5. An apparatus of the class described having a platform and a bell for engaging the platform to provide a treating chamber for a container having a cover loose thereon, comprising a ring rigidly fixed inside the bell, peripherally spaced lifter dogs pivoted to said ring to rock toward and from the cover between first positions free of the cover and second positions of engagement beneath the cover, and lifter shoes pivoted to said ring for engagement with the container as the bell is lowered onto the platform, and effective after such engagement and during further relative movement of the platform and bell to actuate the dogs from said first positions into said second positions.

6. An apparatus as in claim 4, in which the ring also has fixed thereto stop fingers extending into the path of upward movement of the cover whereby to assure maintenance of the cover in condition for accurate replacement upon the container mouth when the bell is raised again.

7. An apparatus having a platform and a bell for covering a container resting on said plat-

form and therewith forming a closed chamber with the container therein, comprising pivot mountings fixed inside the bell adjacent the top thereof, lifting dogs eccentrically pivoted on said mountings so that in a first position each dog can move downwardly free of the projecting edge of a cover on said container and in a second position has been rocked for engaging and lifting the cover from the container, the position of the pivot mountings and the dimensions of the dogs being constructed and arranged relative to the height of the container whereby the dogs engage the container during the downward motion of the bell around the container and are therewith caused to move from the said first position into said second position.

8. A cover lifting apparatus including a support for receiving a container having a mouth with a loose cover thereon, and a bell effective in one position for sealing the interior of the container from the atmosphere, said bell and support being guidedly movable upwardly and downwardly relative to one another, and in combination therewith a pivot connection carried by said bell, and a cover lifter dog on said pivot connection and normally suspended by its weight from said pivot in a position out of engagement with the cover during a major portion of the said upward and downward movement, said dog having a nose and a rounded actuating surface for engagement during the relative downward movement thereof wherewith the nose of the dog is caused to rock inwardly and upwardly into engagement beneath the cover and then to raise the cover from the container mouth.

9. An apparatus of the class described for a container having a mouth with a loose cover thereover, a container support and a bell for engagement with said support, means effective during relative movement of the support and bell for positioning the bell relative to the container and providing a treating chamber enclosing the cover, and lifting means carried by the bell and including a movable part located out of the path of relative movement of the container cover during one portion of the said relative movement so that it is moved past the cover, said lifting means being positioned for actuation by the effect of and during a later portion of said movement whereby the said movable part is shifted to a position to engage and lift the cover.

10. An apparatus having a support for receiving a container having a mouth with a loose cover thereover, and cover lifting means including a movable member, means for moving and guiding the said member in a substantially vertical direction relative to the container support, said cover lifting means also including a first part movably carried by the member and normally positioned so that it does not engage the cover during the downward movement and a second part which moves freely downward with said member during the first portion of the downward movement and is detained during the latter portion of the downward movement of the member and is effectively actuated upon such detention for moving the said first part into engagement with the cover and effecting a raising movement of the same.

11. An apparatus of the class described for a container having a mouth with a loose cover thereover, a container support, a bell, means for guidedly raising and lowering the bell relative to said support and the container thereon so that

in the lowered position the bell is effective for shutting off the interior of the container from the atmosphere, a cover lifting dog having a nose and pivotally suspended from said bell and normally located out of the path of relative movement of the container cover during one portion of the said lowering movement of the bell, and means effective when the dog attains during its downward movement a predetermined distance from the container support to move said dog inwardly until its nose is engaged beneath the cover and then to effect further movement of the dog so that its nose is raised and lifts the cover from the container.
